UNITED STATES PATENT OFFICE.

THEODORE ADOLPH HOOS, OF COLUMBIA CITY, INDIANA.

LIGHTING FIXTURE.

Application filed May 24, 1923. Serial No. 641,226.

To all whom it may concern:

Be it known that I, THEODORE A. HOOS, a citizen of the United States, and a resident of Columbia City, in the county of 5 Whitley and State of Indiana, have invented a new and Improved Lighting Fixture, of which the following is a full, clear, and exact description.

The present invention relates to new and 10 useful improvements in lighting fixtures and it pertains more particularly to chandeliers, wall brackets, and the like.

It is one of the primary objects of the invention to provide a new and improved 15 means for supporting chandeliers, wall brackets, and the like.

It is a further object of the invention to provide means whereby a chandelier, wall bracket, or the like, may be readily removed from its supporting member.

With the above and other objects in view, reference is had to the accompanying drawings, in which—

Figure 1 is a horizontal sectional view of 25 a device constructed in accordance with the present invention and taken on the line 1—1 of Figure 2;

Figure 2 is a view partly in section taken on the line 2—2 of Figure 1; and

Figure 3 is a detail view in section and taken at right angles to Figure 2.

Referring more particularly to the drawings, the reference character 5 designates a ceiling and said ceiling is provided with a 35 suitable passage 6 through which electrical conductors 7 are passed.

Secured to the ceiling by means of screws 8, or the like, is a member 9, said member being in the form of a plate and having 40 a central opening 10. As more clearly shown in Figure 1, this central opening 10 is not circular in form and at diametrically opposite points said opening is formed with notched portions 11.

45 In carrying out the invention, this member 9 is secured to the ceiling by the screws 8, and while in the present instance it has been described in connection with the ceiling, it is obvious that it may be used in connection with side walls without departing from the spirit of the invention.

The reference character 12 designates a chandelier or bracket supporting member and said member 12 has its body portion provided with a centrally disposed screw 55

threaded opening 13, in which a tubular member 14 is adapted to be received.

The body portion of the member 12 is elongated in form and the projecting portions or ends thereof designated by the reference character 15, are provided with screw 60 threaded openings 16.

In assembling the device, after the plate 9 has been secured to the ceiling or wall, the member 12 is positioned therebehind 65 by inserting the ends 15 thereof in the notched portions 11 of the central opening of said plate 9, as shown in dotted lines in Figure 1. After this has been done, the member 12 is turned to the position shown 70 in full lines in Figure 1, in which position the ends 15 of the member 12 will engage the contracted portion of the centrally arranged passage 10 of the member 9. The member 9 is provided with open- 75 ings 20, which, when the member 12 is properly positioned, register with the openings 16 formed therein, and when said openings are in registration, bolts or the like 21 are adapted to be inserted and have 80 threaded engagement with the member 12 to secure the same in position relative to the member 9.

When it is desired to remove the member 12, it is only necessary to remove the bolts 85 21, turn the member 12 to a position where its ends 15 will pass into the notched portions 11 of the centrally arranged opening 10 of the member 9 and withdraw the member 12 from its position behind the mem- 90 ber 9.

From the foregoing it is apparent that the present invention provides a new and improved means for attaching chandeliers to ceilings, which permits of the ready removal of the chandelier without defacing the ceiling or any of the parts associated with the chandelier supporting means.

Having thus described the invention, what is claimed is:

1. A device of the character described, comprising a plate having a central opening, said central opening having oppositely disposed notches, an elongated member adapted to register with said oppositely disposed notches and pass therethrough to position behind the plate, said elongated member being turned out of registry with the notches, and means passing through the plate and into threaded engagement with in- 105 110

ternally threaded openings in the elongated member to secure the same against movement relative to the plate to retain the elongated member in position behind the plate.

5. A lighting fixture comprising a plate, an elongated member adapted to engage behind the plate, means for securing said elongated member in position relative to

the plate, said means comprising bolts passing through the plate and having threaded engagement with opposite ends of the elongated member, and fixture supporting means removably secured to said elongated member. 10

THEODORE ADOLPH HOOS.
